UNITED STATES PATENT OFFICE.

PETER K. BRENNER, OF NEW YORK, N. Y.

RACE-GAME APPARATUS.

1,217,145.

Specification of Letters Patent. Patented Feb. 27, 1917

Application filed May 13, 1916. Serial No. 97,234.

To all whom it may concern:

Be it known that I, PETER K. BRENNER, a subject of the Emperor of Austria-Hungary, residing at No. 849 Stebbins avenue, in 5 the city of New York, State of New York, have invented certain new and useful Improvements in Race-Game Apparatus, of which the following is a full, clear, and exact specification, such as will enable others 10 skilled in the art to which it appertains to make and use the same.

This invention relates to the class of amusement apparatus referred to wherein is employed a table longitudinally movable in 15 opposite directions and upon which, but not secured thereto, is placed a relatively small object, the purpose being to have such object travel from one end of the table to the other without manual manipulation of same, by 20 the employment of the force of inertia.

My invention, among other things, has to do with the means whereby the force of inertia is availed of.

I am aware that I am not the first to employ 25 this force in connection with an apparatus similar in some respects to my present invention. It is also employed in the patent to Goodwin No. 974,376, dated November 1, 1910, and the patent to R. M. Brenner No. 1,011,563, dated December 12, 1911.

In the first mentioned patent, upon a table simulating a race course are placed loosely a series of objects representing race horses. 35 The table is moved backward and forward, on a horizontal plane, and at the completion of the forward stroke, the table is brought in contact with a stationary part on the frame of the machine, which brings the table 40 to a sudden stand-still, while the "horses" continue their forward motion for a slight space. A spring motor and other mechanism are employed to give motion to the table in one direction, pulling against a spring, 45 which latter gives motion in the reverse direction. The race horse remains, as to the table, relatively stationary during both the backward and forward strokes, and continues moving forward when the table is 50 brought to a sudden stop. Thus, by a succession of sharp shocks or jars, the racing object is propelled relatively to the table.

In the patent to R. M. Brenner, the table moves forwardly and upwardly, and backwardly and downwardly, the table being 55 carried by a plurality of oscillating levers which, when the table is in the rearmost position, extend rearwardly upward from their axes of oscillation, at an angle to the perpendicular, and, when the table is in the forward position, are perpendicular. By the motion of the table, the racing objects are carried both forwardly and upwardly; at the end of the forward and upward travel, the table drops downward from under the racing 65 object and at the same time drops backward; thus the object is moved relatively to the table.

In both patents referred to, a series of horses are carried by one table; consequently 70 obstructions are placed in the path of the horses so as to make it problematical which of the horses will win.

My invention differs in structure and principle from both these patents. I preferably 75 employ a table for each horse, and I make the travel of each horse depend upon the player of the game. In other words, to have his horse win, the player must be able to manipulate the devices imparting motion to 80 the table more accurately and deftly than his competitors.

I also provide means whereby announcement is automatically made of the winner of the race, when the first horse crosses the finish line, and, in connection therewith, means 85 whereby further movement of the horses is immediately stopped on such announcement.

My invention also employs improved automatic means whereby the starting barrier is 90 removed at the start of the race.

As the table of my invention does not, in order to move the racing object forward, employ a series of shocks and jars, as in the case of the Goodwin patent, and does not 95 move forwardly and upwardly, and downwardly and backwardly, as in the R. M. Brenner patent, operating, as it does, strictly on a horizontal plane, it is adapted to be noiseless in its operation, which has 100 not been the case with other similar devices.

Furthermore, my apparatus being composed of a few simple parts, it is both easy, and comparatively inexpensive, to install.

The objects and purposes of the invention, as above outlined, will be readily apparent from the following description, taken in connection with the accompanying drawings, in which—

5 Figure 1 is an elevation, partly in section; Fig. 2 is a plan, also showing diagrammatically the main circuit for operating the solenoids and tables;

10 Fig. 3 is a perspective detail, among other things showing diagrammatically a circuit for one table;

15 Fig. 4 is a detail showing diagrammatically a series of tables connected to an announcing device and circuit breaker;

Fig. 5 is an enlarged detail; and

Fig. 6 is a plan of the under side of the part represented in Fig. 5.

Referring to the construction illustrated, 20 10 represents the frame of a booth or enclosure, having at the front, entrances or exits 11, a customary background being provided, as at 12. The apparatus proper comprises a plurality of relatively long and narrow tables 14. Secured to the under surface of each table, at each side thereof, is a guide rod 15, which rods rest within the grooves of rollers 16, which latter may be firmly supported in any desired manner. These guide 25 rods and rollers serve to reduce friction and at the same time prevent the table from moving laterally. The upper surface of the table is provided with a plurality of upwardly projecting guard rails 17.

30 35 Suitably supported, in close proximity to the under side of each of the tables 14 are solenoids 18, 18^a, which, when energized, are adapted to magnetize and draw within their coils the movable members 19, 20. The members 19, 20, being rigidly connected to the table 14, by the uprights 21, are adapted, under the influence of the solenoids, to impart motion, in opposite directions, to the table 14.

40 45 A key 22, operating in the electrical circuit provided by the battery 22^a and associated wiring connected thereto and to the respective solenoids, may be utilized to separately energize first one solenoid and then the other. It will be seen that, when raised from the neutral position indicated in Fig. 1, it will energize the solenoid 18, and when depressed, it will energize the solenoid 18^a. It will be understood that any suitable operating means may be employed in place of the key illustrated.

50 55 In Figs. 5 and 6, I have shown means whereby the solenoids may be moved toward and from each other, for purposes of adjustment, and to regulate the length of travel of the table in each direction, such means comprising a rack 23 on the under side of the solenoid frame, and a pinion 24 meshing therewith, and adapted to be rotated by the crank 25.

60 Loosely placed upon each table is an object intended to represent a race horse and rider. Each horse will bear a certain number, and each table and horse will be operated by an individual key similarly numbered, as indicated in Fig. 1.

65 At the starting end of the racing table, I have provided starting barriers 26, electromagnetically operated by the switch 27, the closing of which energizes the electro-magnet 28, thereby actuating the armature 29, which is rigidly connected, by the upright 30, with a rod 31, and rods 32, at an angle to the rod 31. The barriers 26 being pivotally connected to the rods 32, they rise, out 70 of the path of the horses, when the armature 29 is moved, by the energization of the electromagnet 28, and are again lowered into position when the switch 27 is opened to open the circuit.

75 80 85 At the finish end of the racing table, I have provided means for announcing the number of the winning horse. This means comprises a pair of electrical conducting pieces, 32, 32^a, preferably countersunk in the upper surface of the table. These conducting pieces are part of an electrical circuit including the battery 33 and an annunciator 34. The base-plate 35, upon which are mounted the fore feet of the "horse" is 90 likewise formed of electrical conducting material, and is adapted to close the electrical circuit when it contacts with the conducting members 32, 32^a.

95 100 105 Simultaneously with the announcement of the winning horse, further movement of all the horses on the various tables being operated, is suspended, in the following manner: While each racing table is operated by the player by an independent key, the keys for all the tables preferably take their electrical current from a common source, and in the circuit which includes the operating keys for all the competing racing tables, I include, for example at the point 110 indicated at 38, a circuit-breaker of any suitable construction. One such form of circuit-breaker, and operating means therefor, for opening the key-circuit, I have shown in Fig. 4, wherein are illustrated a 115 series of racing tables having the electrical conducting contact pieces 32, 32^a also shown in Fig. 3 (which pieces, when the circuit is closed, lead to the annunciator 34). To these contact pieces respectively are connected wires leading from the battery 33, in which circuit is included a solenoid 40. A 120 spring-pressed movable member 41 normally in contact with a stationary member 42, closes the break indicated at 38 in the key 125 circuit, but when the solenoid is energized, due to the closure of the gap between the conducting pieces 32, 32^a, on any of the tables, the movable member 41 is moved, against the action of its spring, thereby 130

120 125 130

breaking the further flow of current to the key circuit, and stopping movement of all the horses upon all the tables.

I wish it to be understood that I do not limit myself to two solenoids for each table. I may utilize a solenoid at one end of the table, and in connection therewith, employ a coiled spring, as illustrated in Fig. 5, the solenoid acting to move the table in the direction of the arrow, and the spring causing the table to rebound in the opposite direction, at greater speed.

Furthermore, when using two solenoids, I may also employ two springs, one in connection with each solenoid, or one spring in connection with one of two solenoids. They may be used to supplement the action of the solenoids, or as buffer members, but where two solenoids are employed, such springs are not essential, and it will be found that the natural elasticity of the magnetic lines of force will be sufficient to control the momentum and travel of the tables within definite desired limits.

25 In any case, the ability of the competing players to speed their horses over the simulated race track will depend upon the particular manner in which the operating keys are manipulated. A slight energization of the solenoid which acts to cause motion of the table in one direction (solenoid 18^a, for example), followed immediately by a more lasting energization of the opposite solenoid, will cause motion of the horse, relatively to the table, in the direction of the solenoid 18^a and the finish line, due to the fact that the table moves toward the solenoid 18^a much faster than the movement in the opposite direction. If the energization of the respective solenoids be the converse of that stated, the travel of the horse will be in the opposite direction. This fact makes it possible to operate the racing tables in either direction, or in both directions by duplicating at each end the starting and stopping devices and their connections.

I desire it to be understood that I do not wish to confine myself to the precise details of construction and arrangement of my invention herein set forth, as modification and variation may be made without departing from the spirit of the invention, as defined by the appended claims.

What I claim is:

55 1. In a race game apparatus, the combination of a support, a table thereon free to be actuated in opposite directions, a racing object on said table, operating means, including an electrical circuit and a solenoid in said circuit, for actuating said table to move said object relative to said table, and means for closing and opening said circuit to energize and deenergize said solenoid.

2. In a race game apparatus, the combination of a support, a table thereon free

to move on a horizontal plane in opposite directions, a racing object on said table, operating means, including an electrical circuit and a solenoid in said circuit, for actuating said table, and means for varying the velocity of movement of the table in one direction and thereby move the racing object relative to the table.

3. A race game apparatus, comprising, in combination, a plurality of racing tables for individual players, means for supporting said tables in position to be moved in opposite directions, racing objects on said tables adapted to be moved relative to the table by reverse non-uniform movements of the latter, means, including a solenoid, for actuating said tables to cause such relative movement of said objects, and means controlled by the respective players adapted to govern and control such relative movement.

4. A race game apparatus, comprising, in combination, a plurality of racing tables for individual players, means for supporting said tables in position to be moved in opposite directions, racing objects on said tables to be moved relative to the tables by reverse non-uniform movements of the latter, means, including a solenoid, for actuating said tables, and means controlled by the respective players adapted to govern and control said actuating means and thereby govern and control the relative movement of said objects on said tables.

5. A race game apparatus, comprising, in combination, a plurality of racing tables for individual players, means for supporting said tables in position to be moved in opposite directions, racing objects on said tables to be moved relative to the tables by reverse non-uniform movements of the latter, means, including a solenoid, for actuating said tables, and means controlled by the respective players adapted to govern and control the movements of the respective tables and thereby govern and control the relative movement of said racing objects on said tables.

6. In a race game apparatus, the combination of a plurality of racing tables, means for supporting said tables in position to be moved in opposite directions, racing objects on said tables, operating means, including an electrical circuit and a magnetizable member, for causing said racing objects to move relative to said tables, finish-line markers on each of said tables, and electromagnetic means having connection therewith for announcing the object first crossing the finish-line.

7. In a race game apparatus, the combination of a plurality of racing tables, means for supporting said tables in position to be moved in opposite directions, racing objects on said tables, operating means, including an electrical circuit and a magnetic mem-

ber, for causing said racing objects to move relative to said tables, finish-line markers on each of said tables, electromagnetic means having connection with said markers for announcing the racing object first crossing the finish-line, and electromagnetic means for simultaneously therewith stopping the movements of all the tables and the objects thereon.

10. 8. In a race game apparatus, the combination of a plurality of racing tables, means for supporting said tables in position to be moved in opposite directions, racing objects on said tables, a starting barrier in the path of each of said racing objects, electromagnetic means for raising said barriers, operating means, including an electrical circuit and a solenoid, for moving said racing objects relative to said tables, finish-line markers on said tables, electromagnetic means for announcing the racing object first crossing the finish-line, and automatic means acting simultaneously therewith for stopping the movements of all the tables and the racing objects thereon.

9. In a race game apparatus, the combination of a plurality of racing tables, means for supporting said tables in position to be moved in opposite directions, racing objects on said tables, electromagnetic means for actuating the respective tables in one direction, mechanical means for actuating the respective tables in the opposite direction, and means to vary and control the velocity of movement of the respective tables in one direction.

10. In a race game apparatus, the combination of a plurality of racing tables for individual players, means for supporting said tables in position to be moved in opposite directions, racing objects on said tables, electromagnetic means for actuating the respective tables in one direction, mechanical means for actuating the respective tables in the opposite direction, and means operated by the respective players adapted to vary and control the velocity of movement of the tables in one direction.

11. In a race game apparatus, the combination of a plurality of racing tables, means for supporting said tables in position to be moved in opposite directions, racing objects on said tables, electromagnetic means, including a plurality of solenoids, adapted to operate said tables in opposite directions,

mechanical means supplementing the action of said solenoids, and means operated by the respective players to control and vary the velocity of movement of said tables.

12. In a race game apparatus, the combination of a plurality of racing tables, means for supporting said tables in position to be moved in opposite directions, racing objects on said tables, electromagnetic means, including a solenoid, for actuating said tables in one direction, mechanical means for actuating said tables in the opposite direction at a greater velocity, means operated by the respective players adapted to control the velocity of movement of the tables in one direction, finish-line markers on said tables, and electromagnetic means connected to said markers for announcing the object first crossing the finish-line.

13. In a race game apparatus, the combination of a plurality of racing tables, means for supporting said tables in position to be moved in opposite directions, racing objects on said tables, electromagnetic means, including a solenoid, for actuating said tables in one direction, mechanical means for actuating said tables in the opposite direction at a greater velocity, means operated by the respective players adapted to control the velocity of movement of the tables in one direction, finish-line markers on said tables, and electromagnetic means for stopping the movement of all the tables and the racing objects thereon when one racing object contacts with the finish-line.

14. In a race game apparatus, the combination of a plurality of racing tables, means for supporting said tables in position to be moved in opposite directions, racing objects on said tables, electromagnetic means, including a solenoid, for actuating said tables in one direction, mechanical means for actuating said tables in the opposite direction at a greater velocity, starting barriers in the paths of the racing objects, electromagnetic means for raising said barriers, means operated by the respective players adapted to control the velocity of movement of the tables in one direction, finish-line markers on said tables, and electromagnetic means for stopping the movement of all the tables and the racing objects thereon when one racing object contacts with the finish-line.

PETER K. BRENNER.
